[57] CLAIM

The ornamental design for a pan, substantially as shown and described.

DESCRIPTION

FIG. 1 is a view in perspective of a pan, showing my new design;

FIG. 2 is a view in side elevation thereof as seen from right to left of FIG. 1, the side opposite that shown being a mirror image;

FIG. 3 is a view in side elevation of FIG. 2 rotated ninety degrees about a vertical axis, the side opposite that shown being a mirror image;

FIG. 4 is a view in top plan thereof; and

FIG. 5 is a view in bottom plan thereof.

FIG. 1

FIG. 2

FIG. 3

FIG. 4
